UNITED STATES PATENT OFFICE.

ALBERT BREAKENRIDGE KNIGHT, OF FAIRMONT, WEST VIRGINIA.

CHARGE-FORMING DEVICE.

Application filed May 7, 1927. Serial No. 189,677.

This invention relates to charge forming devices and more particularly to a device for forming explosive mixtures of gas and air.

5 In the glass working industry it is the common practice to use gas burners for glazing and polishing various articles such as tumblers and the like to smooth the edges after the "cracking off" operation, and to 10 smooth the sides of pressed tumblers and the like. When the usual burners and charge forming devices are employed, it has been found that minute particles of carbon are deposited upon and adhere to the articles 15 thus spoiling the appearance thereof. This depositing of carbon particles and the like upon the glassware has been found to be due to imperfect combustion of the gas. The imperfect combustion, in turn, undoubt- 20 edly is due to a great extent to the fact that the air and gas fed to the burners are not perfectly mixed.

An important object of the present invention is to provide a novel charge forming 25 device adapted for use with any form of gas burners, and more particularly to burners used for glazing and polishing glassware, wherein a perfect homogeneous explosive mixture is provided which is adapted to 30 burn cleanly without depositing particles of carbon and the like upon the glassware.

A further object is to utilize a centrifugal blower of novel construction for effecting the formation of the fuel charges.

35 A further object is to provide a charge forming device of the above mentioned character wherein air adjustments are wholly unnecessary to the formation of perfect combustible charges.

40 A further object is to provide a charge forming device employing a centrifugal blower mounted in a housing having a relatively large opening in one side thereof to receive the air to be mixed with the gas, the 45 gas being introduced into the interior of the hub of the blower, which is hollow and provided with perforations through which the gas is drawn by the blower when the latter is rotated, thus permitting the making of 50 a perfect homogeneous mixture of gas and air which is adapted to be perfectly burned.

Other objects and advantages of the in-

vention will become apparent during the course of the following description.

In the drawings I have shown one embodiment of the invention. In this showing:

55 Figure 1 is a side elevation of the blower and associated elements, the gas pipe being omitted,

Figure 2 is a section taken on line 2—2 60 of Figure 1,

Figure 3 is an enlarged detail section on line 3—3 of Figure 2, and,

Figure 4 is a fragmentary perspective 65 view of the rotor.

Referring to the drawings, the numeral 10 designates a blower casing as a whole which is preferably formed of complementary sections 11 bolted together as indicated by the numeral 12. One of the casing sections 11 is provided with a relatively large axial opening 13 through which air is drawn in a manner to be described.

The blower is provided with a tangential outlet passage 14 communicating with an outlet pipe 15 which is adapted to discharge the combustible mixture into a suitable manifold 16, and the flow of the mixture through the pipe 15 may be controlled by a valve 15'. Take-off pipes 17 are connected to the manifold and are adapted to be controlled by valves 18. Any number of the pipes 17 may be employed depending upon the number of burners to be operated, and these pipes may be connected to the manifold at any suitable point.

80 A support 19 is mounted adjacent the casing 10 on the opposite side from the air inlet 13, and a motor 20 is mounted upon this support. The casing 10 is fixed to the support by bolting or otherwise securing it to an upstanding flange 21 preferably formed integral with the support.

85 A rotor indicated as a whole by the numeral 22 is mounted within the casing 10 and comprises a series of radial blades 23 mounted upon a tubular hub 24 and connected at their outer ends by a preferably integral reinforcing band 25. A portion of the hub 24 extends through axial openings 26 formed in the flange 21 and adjacent wall of the casing 10. The projecting portion of the hub is keyed or otherwise secured to the armature shaft 27 of the motor 20 to be driv-

en thereby. The portion of the hub 24 arranged within the casing is provided with a plurality of openings or perforations 28 arranged between each adjacent pair of 5 blades 23.

Gas is supplied to the interior of the hub 24 by a pipe 29. The inner end of this pipe is preferably tapered as indicated at 30 and is arranged adjacent and coaxial with respect 10 to the hub 24 whereby gas will be supplied to the interior thereof. The pipe 29 is supported in proper position by a bracket 30' secured to the blower casing. The pipe 29 is connected to any suitable source of gas supply 15 and a cut-off valve 31 is arranged in the pipe 29.

The operation of the device is as follows: When it is desired to operate burners connected to the pipes 17, the motor 20 is 20 started and any of the valves 18 opened depending upon the burners to be used. The valve 31 is then opened, and the action of the blower draws air into the blower casing through the opening 13, and at the same 25 time creates a depression within the hollow hub 24 thus causing gas to be drawn thereinto. This gas is evenly fed outwardly into the spaces between the blades 23 due to the centrifugal force generated by the latter, 30 the plurality of openings 28 serving to feed the gas in a number of small streams. The rotating action of the blades 23 not only serves to draw in air and gas in the manner described, but also greatly agitates them so 35 as to provide an efficient combustible mixture. In practice, the areas of the openings 28, air opening 13, and the inner end of the pipe 29 are designed so that a given proportion of air and gas are drawn into the 40 casing. It has been found that this proportion is not disturbed by differences in the rotative speed of the blower, nor by the greater or less number of burners operated. The thoroughly agitated and mixed combustible mixture is supplied under pressure 45 to the manifold 16 from whence it is delivered to any of the desired burners. In practice, it has been found that the present device is particularly adapted for use in connection with burners employed in glazing and polishing glassware, and when so employed, the combustion is so perfectly effected that no foreign particles are deposited upon the ware to adhere thereto. 50

It will be apparent, however, that the device 55 is not limited in its use to glazing and polishing burners, but may be used as a charge forming device for supplying combustible gas mixtures to any forms of gas burners. 60

It is to be understood that the form of the invention herewith shown and described is to be taken as a preferred example of the same, and that various changes in the shape, size and arrangement of parts may be resorted to without departing from the spirit 65 of the invention or the scope of the subjoined claims.

I claim:

1. A device of the character described comprising a blower casing having an air inlet opening, a centrifugal blower including a plurality of blades mounted in said casing, said blower being provided with a hollow hub having openings therethrough, 75 and a pipe having its outlet end arranged adjacent said hub and adapted to deliver gas to the interior of said hub.

2. A device of the character described comprising a blower casing having a relatively large axial air inlet opening in one side thereof, a centrifugal blower, including a plurality of blades mounted in said casing, said blower being provided with a tubular hub having radial openings therethrough arranged between said blades, one end of said hub being open, and a pipe having its outlet end arranged adjacent the open end of said hub and adapted to deliver gas to the interior thereof through its 80 open end.

3. A device of the character described comprising a blower casing having an axial air inlet opening in one side thereof, a centrifugal blower including a plurality of blades mounted in said casing, said blower being provided with a tubular hub arranged axially in said casing and having an open 85 end communicating with the exterior of said casing through said air opening, said hub being provided between said blades with a plurality of relatively small openings, and a pipe arranged axially with respect to said casing and having its end disposed adjacent the open end of said hub. 90

In testimony whereof I affix my signature.

ALBERT BREAKENRIDGE KNIGHT.
